UNITED STATES PATENT OFFICE.

EDWIN F. KIECKHEFER, OF MILWAUKEE, WISCONSIN.

CABLE EQUALIZER.

Application filed June 9, 1924. Serial No. 718,879.

This invention relates to certain new and useful improvements in cable equalizers and refers more particularly to a device of this character adapted for use in connection with freight and passenger lifts or elevators.

Where two or more cables are employed in connection with a lift or elevator, it is desirable that means be provided to insure an even distribution of stress therebetween 10 and this invention contemplates as one of its objects the provision of an equalizer employing a fluid medium for distributing or equalizing the stress between the cables.

It is another object of this invention to 15 provide a cable equalizer having a plurality of connected cylinders or bores having therein pistons to which the actuating cables are connected, the cylinders or bores being filled with a suitable fluid medium whereby the 20 stress on the various cables is equalized.

A further object of this invention resides 25 in the provision of a cable equalizer of the character described having means for substantially directly connecting the cables with the lift or elevator in the event the equalizing 30 fluid is released.

This invention has as a still further object the provision of an equalizing device 35 of the character described which is of compact construction permitting its ready attachment to elevators or lifts at the time of their construction or to elevators or lifts now in use and which affords a resilient connection between the cables and the lift or elevator.

With the above and other objects in view which will appear as the description proceeds, my invention resides in the novel construction, combination and arrangement of 40 parts substantially as hereinafter described and more particularly defined by the appended claims, it being understood that such changes in the precise embodiment of the herein disclosed invention may be made 45 as come within the scope of the claims.

In the accompanying drawing, I have illustrated one complete example of the physical embodiment of my invention constructed according to the best mode I have so far 50 devised for the practical application of the principles thereof, and in which:

Figure 1 is a fragmentary perspective view 55 of the top portion of a lift or elevator equipped with an equalizer embodying my invention;

Figure 2 is a view of my improved equalizer detached from the lift or elevator looking on the plane of the line 2—2 of Figure 1, said view being partly in top plan and partly in section and a portion of the head 60 or top plate being broken away to illustrate details of construction, and

Figure 3 is a view, partly in section and partly in elevation, taken transversely through Figure 2 on the plane of the line 65 3—3.

Referring now more particularly to the accompanying drawing, in which like numerals designate like parts throughout the several views, the numeral 5 designates a 70 lift or elevator, which may be of either the passenger or freight type, having a supporting frame-work including side members 6, but one being shown, connected at their upper ends by a pair of spaced parallel channel beams 7 mounting bearings 8 at their ends which engage the shaft guide rails 9, but one being shown. The cables 10 for actuating the lift or elevator are connected with the supporting frame-work medially 75 of the beams 7 by my improved equalizing device 11, now about to be described.

The equalizing device is preferably constructed from a single block 12 of a width to fit in the space between beams 7 and having opposite, laterally extended flanges 13 engaging the lower flanges 14 of the channel beams to which they are secured by fastening members 15. The block 12 is provided with two sets or groups of vertical bores or 80 cylinders 16 and 17 which are closed at their upper ends by a head or plate 18 removably secured to the block by suitable fastening means 19. The joint between the removable head and the block is made fluid 85 tight by the provision of a suitable gasket 20.

The cylinders of one group are staggered with respect to the cylinders of the other, as best illustrated in Figure 2, and passed thereinto through openings 21 in the head 100 18 are rods 22 having pistons 23 mounted thereon and working in the bores or cylinders. Upward movement of the pistons beyond a position substantially medially of the ends of the cylinders is resisted by a 105 fluid medium confined between the pistons and the head 18. Leakage of the fluid medium past the rods 22 is prevented by the glands or stuffing boxes 24, as best illustrated in Figure 3.

A passage or channel 25 is formed in the top face of the block medially of the groups of bores or cylinders from which branch passages or channels 27 lead to the cylinders to interconnect the cylinders at their upper ends and permit the fluid medium to pass from one cylinder to another. With the cylinders interconnected, the pistons automatically adjust themselves to equalize the stress on all the cables and the fluid medium displaced from one cylinder by reason of the cable connected with the piston thereof being shorter than the others, is forced or distributed among the other cylinders.

15 The fluid medium is supplied to the upper ends of the cylinders 16 through an inlet or filling pipe 29 threaded in a passage or duct 30 in the head 18 registering with the channel or passage 25. The inlet or filling pipe is normally closed by a removable cap 31 preferably threaded on the filling pipe to withstand the pressure thereon when the fluid in the cylinders is under compression.

20 The pistons 23 are each preferably formed of a leather cup 32 medially secured on its rod 22 between two collar members 33 and 34 confined between nuts 35 and 36, respectively, threaded on the rod and locked against accidental rotation by locking nuts 37. As will be readily obvious, any tendency of the piston to move upwardly compresses the fluid in the upper portion of the cylinder and spreads the leather cup 32 to increase its contact with the cylinder wall and 25 prevent the escapage of the fluid therewith. A drip pan 38 is suspended beneath the block 12 by straps or brackets 39 to catch any of the fluid tending to drip therefrom.

25 As illustrated in Figure 3, the rods 22 extend below the block 12 and have stop washers 40 secured thereon by nuts or other means 41. The stop washers are normally spaced from the block a distance less than the distance between the upper-most lock nuts 37 and the head 18 so that, in the event the fluid medium is released from the cylinders, the cables 10 are substantially directly connected with the lift or elevator by the stop washers 40 abutting the block 12.

30 As will be readily obvious to those skilled in the art to which an invention of this character appertains, the stress on the cables is equalized or distributed by reason of the fluid medium in the upper portions of the cylinders being free to flow from one cylinder to another through the passages of channels 25 and 27 and that the fluid medium provides a substantially resilient or cushion connection between the cables and the lift or elevator supporting frame.

35 What I claim as my invention is:

1. A cable equalizer of the character described, comprising a block member, said block member being provided with groups 40 of cylindrical bores extending therethrough,

the bores of one group being staggered with respect to the bores of another, a head plate secured to the block and closing the upper ends of the bores, rods passed through the head plate and through said bores with their lower ends projected beyond the block member, pistons medially mounted on said rods and having a snug fit with the walls of the bores, means for attaching lifting cables to the upper ends of the rods, passages connecting the upper portions of the bores, a fluid medium adapted to fill the upper portions of said bores and to be compressed between the pistons and the head plate upon the application of stress to said rods, the fluid medium displaced from one bore by reason of unequal stress on the rod therein being distributed to the other bores, and stop members carried by the lower ends of said rods and spaced from the block member a distance less than the distance between the pistons and the plate member, whereby said rods are substantially directly connected with the block member upon release of the fluid medium from the cylinders.

2. A cable equalizer of the character described, comprising a block member, a plurality of cylinders formed in the block member, grooved channels affording communication between the cylinders, a head plate secured to the block member and closing the upper ends of the cylinders, pistons mounted in the cylinders, rods secured to the pistons and passed outwardly of the cylinders through the means closing the upper ends thereof, means surrounding the piston rods at their point of passage through the head member to provide a slidably fluid tight joint, means for securing lifting cables to the upper ends of said rods, and a fluid medium filling the upper ends of the cylinders whereby unequal stress on one piston displaces a portion of the fluid medium therein and said displaced fluid medium being distributed to the other cylinders through the grooved channels.

3. A cable equalizer of the character described, comprising a block member, a plurality of cylinders formed in the block member, channels grooved in the upper face of the block member and affording communication between the cylinders, a head plate secured to the block member and closing the upper ends of the cylinders, pistons mounted in the cylinders, rods secured to the pistons and passed outwardly of the cylinders through the means closing the upper ends thereof, means surrounding the piston rods at their point of passage through the head member to provide a slidably fluid tight joint, means for securing lifting cables to the upper ends of said rods, a fluid medium filling the upper ends of the cylinders whereby unequal stress on one piston displaces a portion of the fluid medium therein and said

displaced fluid medium being distributed to the other cylinders through the grooved channels, and means extended from the head plate for facilitating the insertion of the fluid medium.

4. A cable equalizer of the character described comprising a block member, a plurality of cylinders formed in the block member, means closing the upper ends of the cylinders, pistons mounted in the cylinders, rods secured to the pistons and passed outwardly of the cylinders through the means closing the upper ends thereof and extending below the bottom of the block member, 10 means for securing lifting cables to the up-

per ends of said rods, passages connecting the upper ends of the cylinders, a fluid medium filling the upper ends of the cylinders whereby unequal stress on one piston displaces a portion of the fluid medium there- 20 in and said displaced fluid medium being distributed to the other cylinders through said passages, and stop members carried by the lower ends of the rods and adapted to engage the bottom face of the block member 25 upon release of the fluid medium from the cylinders, to substantially directly connect the rods with the block member.

In testimony whereof I affix my signature.
EDWIN F. KIECKHEFER.
